LAPPING APPARATUS

David A. Wallace, Detroit, Mich., assignor to
Chrysler Corporation, Highland Park, Mich., a
corporation of Delaware

Original application July 22, 1936, Serial No.
91,851. Divided and this application July 1,
1938, Serial No. 216,857

4 Claims. (Cl. 51—67)

This invention relates to improved apparatus for lapping surfaces and is a division of my application, Serial No. 91,851, filed July 22, 1936.

More particularly the invention pertains to 5 lapping of surfaces of apparatus and parts thereof which operate in rubbing, sliding or rotative bearing-like, or frictional contact with other parts.

Heretofore, in polishing, lapping or otherwise 10 finishing surfaces, it has been the practice to produce relative movement, mainly in one direction only, between the surfaces of the work and the lapping means. In some instances combinations 15 of different directional movements have been employed in an effort to avoid scoring of the surface operated upon by repeated action of isolated hard particles of the lapping element on substantially the same areas of the work. The relative movement in one direction has, however, been of a 20 relatively low order of velocity as compared to the relative movement in another direction, and consequently, the scratch lines, scores, or inscriptions traced on the work by isolated hard particles in the lapping surface have not been or disturbed and cross-hatched as to provide finished 25 surfaces of actual mirror-like smoothness directly by lapping operations.

Polishing with extremely fine abrasives, such 30 as rouge, has been required after the lapping operation, to produce the desired degree of smoothness and finish. In this connection it should be noted that while polishing of this character improves the appearance of the surfaces 35 it does not materially change its physical smoothness. That this is true can readily be seen by microscopic observation of conventionally lapped and polished surfaces by which it is found that the multiplicity of minute ridges between adjacent scratch lines or scores are not actually removed. The polishing compound merely forms 40 a luster on the sides of such ridges which give the final surface an appearance of much greater smoothness than actually exists.

I have found that by producing relative movements of respectively different ranges of speed 45 and in different directions, preferably at right angles, between the surface operated upon and the lapping surface, actual smoothness is directly obtained by lapping and such smoothness is of 50 a much different and superior kind than that resulting from conventional lapping followed by polishing operations.

Another object of the invention is to provide improved lapping apparatus by which physically smooth and mirror-like surfaces can be directly

formed by lapping operations without producing a deceitful luster such as that formed by polishing the side surfaces of ridges of presumably, but not actually, smooth surfaces.

A further object of the invention is to provide 5 apparatus of this character by which the inscriptions traced on the surface operated upon by localized hard particles in the lapping surface can be brought to a desired angular cross-hatched relationship such that the resulting scratch lines 10 are accordingly so repeatedly cross-hatched as to destroy their normal roughness producing effect.

An additional object of the invention is to provide apparatus of this character by which the 15 reciprocating movement of the lapping element is maintained at a sufficiently high velocity and frequency to produce smooth surfaces free from grooves and scores with a limited amount of reciprocatory movement. 20

A still further object of the invention is to provide apparatus of this character by which a lapping element can be conveniently reciprocated, during application thereof to a rotating piece 25 of work, at a relatively high rate of speed of a vibratory order.

A still further object of the invention is to provide an improved lapping device which will operate a plurality of conveniently attachable and detachable lapping elements so as to facilitate 30 adaptation of the device to the lapping of a plurality of different types of pieces of work.

Another object of the invention is to provide 35 lapping apparatus of this character by which the relative movement between the lapping element and the work in one direction is of a reciprocatory nature and which movement varies in velocity from zero at opposite ends of the stroke while maintaining a substantially high velocity through out the main portion of the 40 stroke.

Other objects of the invention are to provide 45 improved lapping element holders by which a plurality of lapping surfaces can be held against the work with substantially uniform pressure; to provide an improved lapping device by which the inner surfaces of annular members such as brake drums and cylinders can be lapped in accordance 50 with the invention.

Illustrative embodiments of the invention are shown in the accompanying drawing, in which:

Fig. 1 is a longitudinal vertical sectional view of apparatus for lapping internal cylindrical surfaces of articles.

Fig. 2 is a fragmentary transverse vertical sectional view taken on the line 2—2 of Fig. 1.

In the form of the invention illustrated in the drawing, both the rotative movement of the work and the reciprocatory movement of the lapping elements operating thereon are produced by suitable driving means. In this form of the invention the lapping apparatus comprises a stationary casing 70 provided with spaced bearings 80 in which a tubular shaft 81 is journaled. Mounted on the tubular shaft 81 is a worm wheel 82 which is driven by a worm 83 operatively connected, in turn, to a prime mover such as an electric motor or other suitable driving mechanism. The shaft 81 has a bevel gear 84 non-rotatively fixed thereto which is meshed with bevel pinion teeth 85 formed on the inner end of a stub shaft 86. The stub shaft 86 is journaled in a bearing 87 mounted in the wall of the casing 70 and has an external end provided with an eccentric pin 88. Slidably mounted in a channel 89 formed on the exterior of the casing 70 is a slide block 90 on which a lapping element holder, generally designated by the numeral 91, is mounted. The slide block 90 has a recess in its lower side for receiving the eccentric pin 88 and by the agency of which the block 90 is reciprocated.

A shaft 92 extends axially through the tubular shaft 81 and is supported at its left end, as revealed in Fig. 1, by a dead spindle 93, the right end of the shaft 92 being supported by and operatively connected with a live spindle 94 by which it is rotated. Provided on the left end portion of the shaft 92 are a pair of coupling members 95 and 96 for non-rotatably attaching to the shaft 92 an article, such for example as a vehicle wheel brake drum 97 which has an internal cylindrical surface 98 to be lapped. The article to be operated upon may be secured to the shaft 92 in any desired manner, the form of attachment shown in the drawing being merely for illustrative purposes. In this case, the brake drum is detachably and drivingly secured to the shaft 92 by axial pressure of the coupling element 95 on a hub part 99 on which the drum 97 is mounted, such axial pressure being resisted by a thrust ring 100 which bears against the coupling element 96.

The lapping element holder 91 comprises a flexible and resilient backing element 100', preferably formed of resilient sheet metal, on one side of which are mounted a plurality of sockets 101 in each of which is disposed a lapping element 102. The lapping elements may comprise a stone structure or any other polishing material. The intermediate portion of the lapping element holder 91 is yieldably urged outwardly to press the lapping elements into operative engagement with the surface 98 of the drum by a pair of coil springs 103, each of which is located in a slot 104 formed in the slide block 90 and which bear between the bottom of the slot 104 and the lower side of the flexible backing strip 100'. The lapping element holder is held against excessive outward movement by the springs 103 by a stem 105 which extends through the wall of the casing 70 and which is provided with the head 106 having an elongated slot 107 formed therein. The head 106 is received between a pair of aperture lugs 108 carried by the flexible backing 100' and it is movably attached to the lugs 108 by a pin 110, as illustrated in Fig. 2. Provided on the lower end of the stem 105 is a nut 111 which is adapted to engage an abutment 112 to prevent excessive outward movement of the lapping ele-

ment holder. The pin and slot connection between the stem 105 and the lapping element holder accommodates reciprocatory movement of the latter during operation of the device. It is to be understood that in this form of the invention the relative velocity of reciprocatory and rotative movements of the lapping elements and brake drum, respectively, are predetermined in the following manner.

In order to assure the application of uniform pressure upon the surface 98 by all the lapping elements 102, it is preferable to so form the resilient yieldable backing 100' of the holder that when it is in its relaxed state, it will have a greater radius of curvature or less actual curvature than the surface with which it is intended to bring the lapping elements into conformity. Thus, when pressure is applied at the intermediate portion of the backing 100' all lapping elements are applied to the surface operated upon at substantially uniform pressure.

During operation of the foregoing apparatus the work is rotated continuously in one direction and the lapping elements are reciprocated in a direction substantially parallel to the axis of rotation of the work. The linear velocity of these respective different directional movements are so predetermined as to bring the resultants of the movements during successive half cycles of the reciprocatory movement into predetermined angular relationship with respect to each other. It is preferable to cause the resultants of the movements produced during successive half cycles of the reciprocatory movement to intersect at substantially right angles of each other. To accomplish this, the linear velocity of the surface operated upon and the linear velocity of the lapping elements must be substantially equal. However, since the velocity of the reciprocatory movement varies, this condition is not maintained at all times but is approached throughout the main portions of the strokes of the lapping elements. Localized hard areas of the lapping surface, therefore, trace inscriptions on the surface of the work during successive half cycles of the reciprocatory movement which are cross-hatched at a plurality of different angles forming an heterogeneous arrangement of cross-hatched scratch lines, none of which develop into deep grooves or scores. While it is preferable to so predetermine the linear velocity of the movement of the work and movement of the lapping elements as to bring the main portions of the scratch lines to approach right angle relationship with respect to each other, it is found that excellent results are obtained when the angularity of the lines traced during successive half cycles of the reciprocatory movement is such that the minimum angle therebetween is substantially forty degrees. In other words, the resultant of the two directional movements may vary from an inclination of substantially twenty to substantially seventy degrees to the path of reciprocatory movement. For the purpose of illustration, a cylindrical surface of substantially three and one-eighth inches in diameter would be rotated at approximately sixty R. P. M. and the lapping elements would be reciprocated at a rate of substantially 900 cycles per minute.

In the lapping of surfaces in accordance with the invention during which the lapping element is reciprocated at a relatively high speed, it is found that the abrasive action of the lapping elements is rapid while the ridges formed during turning or other machining of the surfaces are

being removed. As soon as the ridges are removed to their base line, the abrasive action decreases materially and further removal of metal is substantially discontinued. By virtue of this characteristic of the improved lapping process surfaces can be brought to a high degree of smoothness in a relatively short time and without danger of removing sufficient material to render the articles undersize. The smoothness resulting from the actual removal of the ridges without introducing other ridges by application of the lapping elements to the surface, is of much superior order than the mere lustrous finish resulting from polishing the side surfaces of the ridges. The large number of strokes of the lapping elements across the ridges in a direction substantially normal to their lengths, resulting from reciprocation of the lapping elements at a rate of a vibratory order, assures removal of the ridges and not mere polishing or partial flattening thereof.

Although but one specific embodiment of the invention has been herein shown and described, it is understood that various changes of details of construction and operation may be made without departing from the spirit and scope of the invention.

What I claim is:

1. Lapping apparatus including means for rotatably supporting an article having a recess and an associated internal cylindrical surface, driving means for rotating said article, a stationary support insertable into said recess, a reciprocable lapping element slidably mounted on said support and engageable with said surface throughout a major portion of its axial dimension, said lapping element comprising a flexible base portion conforming to the curvature of said surface and a plurality of circumferentially spaced abrading stones, and means on said support for independently drivingly reciprocating said lapping element during rotation of said article, said means being so constructed and arranged as to impart to said lapping element a linear abrading reciprocating movement of a short stroke of substantially less length than the length of contact between said surface and said lapping element and of substantially the same order of velocity as the velocity of the linear movement of said surface.

2. Finishing apparatus including means for rotatably supporting a piece of work having an opening therein surrounded by a curvilinear surface, means for drivingly rotating said work, a support insertable into said opening, an abrading tool reciprocably mounted on said support comprising a base portion and a resiliently deformable head conformable to the curvature of said surface

and having a plurality of spaced abrading stones thereon engageable with said surface, and means on said support for drivingly reciprocating said tool throughout a short stroke comprising only a small fractional part of the axial dimension of said surface during rotation of said work, said means being so constructed and arranged as to impart to said tool a linear movement of substantially the same order of velocity as the velocity of the linear movement of said surface and resilient means acting upon said deformable head at the central portion thereof for urging said stones against said surface.

3. Apparatus for finishing a piece of work having an opening therein surrounded by an internal surface portion to be finished including relatively rotatable support members for said work and for a finishing tool respectively, said tool support member being insertable into said opening, said tool comprising a flexible head reciprocably mounted on said tool support member and having a plurality of circumferentially arranged abrading elements engageable with said surface, means for urging said abrading elements against said surface, guide members on said tool support for confining the reciprocatory movement of said tool to a course in the direction of the axis of said relative rotation, means for drivingly producing relative rotation of said work and tool support members, and means for drivingly reciprocating said tool relative to said tool support member during relative rotation of the latter and said work.

4. Apparatus for lapping a piece of work having an opening therein bounded by an internal surface portion to be lapped including relatively rotatable support members for said work and for a lapping tool respectively, said lapping element support member being insertable in said opening, a lapping tool comprising a base portion reciprocably mounted on said lapping tool support member and a resiliently yieldable head portion having a plurality of lapping elements thereon engageable with said surface, means acting between said tool and said tool support member including resilient members for urging the latter toward said surface, guide members on said tool support member for confining the reciprocatory movement of said tool to a course in the direction of the axis of said relative rotation, mechanism for drivingly producing relative rotation of said work and tool support members, and means for drivingly reciprocating said tool relative to said tool support member during said relative rotation of the latter and said work support member.

DAVID A. WALLACE.
